NESTOR LEONARD, OF FEIGNIES, FRANCE.

WHEEL FOR LOCOMOTIVES AND OTHER PURPOSES.

Application filed August 18, 1925, Serial No. 51,025, and in France March 5, 1925.

Steel wheels for locomotives as hitherto constructed have elements of very unequal metallic thicknesses; the hub and the counterpoise are masses far thicker than the 5 spokes and the rim; consequently large difficulties arise in manufacture. In effect, the wheel, at the instant of solidification of the steel, is subjected to considerable shrinkage stresses; there is first a circumferential 10 shrinkage of the rim towards the hub, a circumferential shrinkage of the hub towards its centre, shrinkages of the counterpoise towards its centre, and finally shrinkages of each spoke towards its centre. 15 These last shrinkages result from the fact that the middle portion of each spoke cools fastest, as it is most remote both from the metal in course of cooling to form the rim and the metal in course of cooling to form 20 the hub.

To sum up, irregularly distributed shrinkages and stresses are set up in the wheel.

These difficulties have in part already 25 been remedied as regards the counterpoise, by providing within the mould, before pouring, cooling blocks of steel which promote the cooling of the counterpoise and render uniform the shrinkage of the piece. 30 By the aid of a core, a chamber has also been provided inside the counterpoise, this chamber being filled, after the casting, with an additional mass of molten metal, lead for example; this last method serves to render uniform the thicknesses of the cast 35 metal in order to obtain uniform cooling and shrinkage.

However, the following difficulty has never hitherto been remedied in the wheels 40 of locomotives; the middle of the spokes which is the portion of these spokes most cooled and consequently the most quickly solidified, exerts a powerful tension on a zone of the mass of metal not yet solidified 45 which goes to form the hub.

The feeding head certainly has the function of constantly feeding with molten metal the mass in course of cooling; however considering the number of zones of 50 tearing away (in number equal to the number of spokes), the slight extent of these zones and the plastic condition of the metal

which at this moment constitutes the hub, it is obvious that the action of the feeding head is insufficient to combat the tension of 55 the spokes on the hub; these tensions have occasionally the effect of producing cracks in the hub.

These cracks cannot weld themselves up again owing to the oxidation which is instantaneously produced at the time of the premature cooling of the spokes relatively to that of the hub.

Under these conditions, the hub can no longer present the desired solidity to transmit with all certainty to the rim the considerable stresses to which it is subjected; under vibration, it can expand on its axle and become unkeyed, which, with locomotive wheels, may cause grave accidents. It 70 is for this reason that the chief engineers of great railway companies, who have the responsibility for the rolling stock, show themselves so difficult in accepting these pieces, to such a degree that they will not 75 authorize even the repair by autogenous welding, which results in steel works having a large number of rejections.

The present invention relates to a wheel 80 for locomotives or other purposes which enables the above defects of existing arrangements to be avoided. This wheel has for its feature that a certain number of spokes instead of connecting the rim to the hub by being directly attached to the hub, are on 85 the contrary merged into adjoining spokes, in such manner that the number of points of attachment of the spokes to the hub are reduced and consequently the number of 90 zones of tearing away of the spokes from the hub at the instant of solidification, the feeding head then being able to feed without difficulty this small number of zones of tearing away and avoiding the formation of 95 cracks in the hub.

The invention extends also to other features hereinafter described and to their various combinations.

A locomotive wheel according to the invention is illustrated by way of example 100 on the accompanying drawing in which:

Fig. 1 is an elevation of the wheel, and Fig. 2 a section thereof along the diverted line 2, 2, 2 of Fig. 1.

The wheel comprises two series of spokes 5¹ and 5². The spokes 5¹ are directly attached to the hub 1 whilst the spokes 5² are each merged into the two respective adjoining spokes 5¹ by two branches 20¹, 20², these two branches providing between them and the hub 1^a triangular free space 21.

These various arrangements ensure the following technical advantages:—

1^a First the number of points of attachment on the hub 1 is reduced to half the number of the spokes, the spokes 5¹ only being attached to the hub. Consequently the number of tearing away zones 15 is also reduced to a half. These zones 15, thus reduced in number, become uniformly fed by the feeding head 16 during solidification, which avoids any formation of cracks in the hub 1.

Moreover, recesses 25 formed in the rim opposite each spoke 5² avoid the suction of the metal in the direction 10 at the intersection of the spokes and the rim.

Finally, the spokes 5¹, being connected to the rim, not directly, but through the medium of branches 22¹, 22², present an elasticity comparable with that of the spokes 5², notwithstanding the quite different mode of joining of the spokes 5¹, 5² and the hub 1.

In addition, in order yet to increase the elasticity of the wheel, the spokes 5² of the second series may be connected to the rim through the intermediary of two branches 30¹, 30², these two branches providing between them a free space 31, as shown in Fig. 1.

To sum up, the locomotive wheel according to the invention avoids cracks in the hub,

whilst leaving all the spokes approximately equal elasticities.

Claims:—

1. In a cast metal wheel for locomotives and similar purposes, the combination of a hub, a rim concentric with said hub, a series of spokes attached to said hub and rim, a second series of spokes attached to said rim and to the spokes of said first mentioned series of spokes, each spoke of said second mentioned series being attached to two adjoining spokes of said first mentioned series, thus reducing the number of points of attachment of said spokes to said hub. 40

2. In a cast metal wheel for locomotives and similar purposes, the combination of a hub, a rim concentric with said hub, a series of spokes attached to said hub and rim, each said spoke being attached to said rim by branches, a second series of spokes attached to said rim and to the spokes of said first mentioned series, the spokes of said two series thus presenting approximately equal 50 elasticities. 55

3. In a cast metal wheel for locomotives and similar purposes, the combination of a hub, a rim concentric with said hub, a series of spokes attached to said hub and said rim, each spoke of said series being attached to said rim by branches, a second series of spokes attached to said rim and to said spokes of said first mentioned series, each spoke of said second series being attached to 60 said rim by branches, thus increasing its elasticity. 65

In testimony whereof I affix my signature.

NESTOR LEÓNARD.
